UNITED STATES PATENT OFFICE.

BERNHARD SPITZFADEN, OF BROOKLYN, NEW YORK.

SELF-CLOSING AND CONTROLLING MEANS FOR DOORS.

1,423,467.

Specification of Letters Patent. Patented July 18, 1922.

Application filed September 30, 1920. Serial No. 413,839.

To all whom it may concern:

Be it known that I, BERNHARD SPITZFADEN, a citizen of the United States, and a resident of the city of New York, borough of Brooklyn, in the county of Kings and State of New York, have invented a new and Improved Self-Closing and Controlling Means for Doors, of which the following is a description.

10 My invention relates to self-closing doors, such for example as elevator doors and means to control the door-closing means, the invention being adapted to be employed either for closing a single door or sectional door.

15 The nature of the invention, its distinctive features and advantages can best be stated in connection with the description of practical embodiments thereof as hereinafter given.

20 Reference is to be had to the accompanying drawings forming a part of this specification, it being understood that the drawings are merely illustrative of practical examples of the invention.

25 Figure 1 is a front elevation of devices embodying my invention, showing the same employed in connection with a single sliding door;

Figure 1^a is a perspective view of a latch 30 member and its operating handle;

Figure 2 is a plan view of the device as shown in Figure 1 and the doors to which the devices are applied, the door frame being in horizontal section;

35 Figure 3 is an enlarged plan view of the door cushioning means and the adjacent parts;

Figure 4 is a front elevation of devices embodying my invention applied to a sectional door, the door sections being shown in the open position;

Figure 5 is a view similar to Figure 4 but showing the sectional doors in the closed positions.

45 The letter A indicates a door frame; B, a sliding door; C, a fixed door panel; D, a track rail above the doors; and E, hangers for door B provided with rollers F traveling on rail D, said parts being of any approved 50 form.

Referring first more particularly to the construction shown in Figure 1, the numeral 10 indicates a vertically disposed guide bar

which in the form of the invention, Figure 1, is fixedly secured to the door frame A as 55 by bracket plates 11. A sleeve 12 is slidable on the guide bar 10 and pivoted thereto as at 13 is one end of a door closing lever 14, the opposite end of which has means affording a fulcrum for said lever on door B. 60 In the illustrated form the lever 14 is fulcrumed as at 15 on a plate 16 secured in any suitable manner to sliding door B.

The lever 14 is formed with a latch projection 19 below the fulcrum 15, the provision of which projection 19 gives said lever the form of a bellcrank and the projection coacts with a latch as hereinafter described. To the lever 14, slightly distant from fulcrum 15, is suitably secured by brazing or 65 otherwise, one end of a spring 21 which advantageously may, as shown, be a flat-coil spring. The opposite end of said spring is secured as at 22 to the plate 16 or otherwise fixedly secured to the door B. 75

A latch 23 is provided adjacent to the projection 19 and has a notch 24 adapted to receive the pointed end of said projection for holding the lever 14 against movement when the door B is closed, thereby latching the 80 door. Said latch member 23 is formed as an arm of a bellcrank lever 25, the other arm of which constitutes a handle for operating the device for opening the door, said handle having a suitable hand grip 26 or the like. 85 The numeral 27 indicates the fulcrum of the bellcrank latch lever 25, and 28 indicates a spring here shown as a plate spring, bearing at one end against said latch lever and secured at its opposite end to plate 16 or 90 other fixed part. The plate 16 may be a part of a housing 29 for enclosing the springs 21, 25, and adjacent portions of the levers 14 and 25.

In the closed position of the door B the 95 lever 14 is at such an angle to the vertical guide bar 10 that a sliding of the door B toward the open position will cause the sleeve 12 and the adjacent end of the lever 14 to rise to the dotted line position of 100 Figure 1.

With the above described construction, the door B being closed, in order to open the door the hand grip 26 is grasped and the latch lever 25 rocked to disengage the 105 notched latch arm 23 thereon from the pro-

jection 19 of lever 14, thereby releasing said lever and permitting it to rock on its fulcrum 15. Pressure is now exerted on the lever 25 in a direction to slide the door B to the open position. When the door B is released by the operator it will automatically close by the reaction of the spring 21 which will have been wound up by upward movement of the lever 14, as indicated by the dotted lines. Thus, in the reaction of the spring it will exert a pressure on the lever 14 causing said lever to move to the full line position of Figure 1, the action of the lever 14 in its relation to the door B being similar to a toggle.

The illustrated door-cushioning means bearing the reference characters 32 to 39 forms no part of the invention claimed in this application.

In Figures 4 and 5 my invention is employed in connection with sliding door sections B', B²; in so far as the parts in Figures 4 and 5 correspond with the first-described arrangement they bear the same identifying reference characters. For operating the door sections B', B², the guide bar 10^a corresponding with bar 10 is secured as by brackets or straps 11^a to the inner door sections B' to slide therewith. The sleeve 12^a corresponding generally with the sleeve 12 has secured thereto at the opposite side from lever 14 a toggle link 42 which is pivoted at its upper end as at 43 to said sleeve, the opposite lower end of link 42 being pivoted as at 44 to a bracket 45 secured to the door frame A. In Figures 4 and 5 the fulcrum 15 is conventionally shown as directly on the outer door section B². The same is true of the fulcrum pin 27 of the latch lever 25. Similarly, the springs 21, 28 have one end secured as at 22, 28 directly to the door section B². When the latch lever 25 on door B² is rocked to release the latch arm 23, from projection 19, the door section B² may be slid toward the open position thereby causing the lever 14 to move sleeve 12^a upwardly and causing the door section B' to move also to the open position, the link 42 rocking on its pivots 43, 44. Thus, the parts will assume the positions shown in Figure 4 when the door sections are open.

It is to be noted that the lever 14 is not dead centered when the doors are closed and that said lever will always be in a position to readily respond to an opening movement of the door B or door section B². It is to be further noted that the lever 25 constitutes the means for releasing the latch arm 23 as well as the handle for sliding the door or door section to the open position.

I would state in conclusion that while the illustrated examples constitute practical embodiments of my invention, I do not limit myself strictly to the mechanical details herein illustrated, since manifestly the same

can be considerably varied without departure from the spirit of the invention as defined in the appended claims.

Having thus described my invention, I claim:

1. A self-closing means for doors including a vertical guide rod, a vertically sliding element thereon, a lever pivoted to said element and adapted to be pivoted at its opposite end to a door, and spring means exerting its pressure at one end on said lever and adapted at its opposite end to be secured to the door, said means normally tending to rock said lever in a direction to move the said lever for closing the door. 80

2. A door operating means including a lever adapted to be fulcrumed on a door for closing the latter, guide means for the opposite end of the lever, and a spring exerting its pressure at one end on said lever and adapted to be connected with the door and tending to move the lever in a direction to close the door. 85

3. A door closing means including a lever adapted to be fulcrumed adjacent to an end thereof on a door for closing the latter, guide means for the opposite end of the lever, said lever having a latch member adjacent to the fulcrum, and a latch adapted to be pivoted on the door adjacent to the fulcrumed end of the lever and having an arm to engage the latch projection on the lever, said latch having a handle for rocking the same and for use in moving the door to the open position after release of the latch. 95

4. A door closing means including a lever having a latch projection giving the lever a bellcrank form, said lever being adapted adjacent to said projection to be fulcrumed on a door for closing the latter, guide means for the opposite end of the lever, a latch for engaging said latch projection and adapted to be mounted on a door, and a coil spring exerting its pressure on said lever and to a relatively fixed part for imparting to the lever a door closing movement. 105

5. A door operating means including a toggle lever adapted to be fulcrumed at one end on a door and mounted at its opposite end for pivotal and vertically sliding movement, a latch, and means to mount said latch on a door independently of said lever but in position to engage or disengage the lever adjacent to its fulcrum. 115

6. The combination with a sliding door of a vertical guide bar adjacent to said door, a slide on said bar, a lever pivoted at one end to said slide and fulcrumed on said door in position to be inclined to said bar when the door is closed, and a latch adapted to be mounted on a door and to engage or disengage said lever. 125

7. The combination with a sliding door of a vertical guide bar adjacent to said door, 130

a slide on said bar, a lever pivoted at one end to said slide and fulcrumed on said door in position to be inclined to said bar when the door is closed, a spring acting on 5 said lever tending to move the same for closing the door, said spring exerting its pressure at one end on the lever and secured at its opposite end to said door, and a latch adapted to engage or disengage said 10 lever.

8. In means whereby to open or close a door, a substantially vertical guide, a slide on said guide, a lever pivoted at one end on said slide, and means to fulcrum said 15 lever on a door to be disposed in all its positions at an angle to said guide; together

with a spring exerting its pressure on said lever and adapted to be connected with the door to impart a closing movement to the door. 20

9. In means whereby to open or close a door, a substantially vertical guide, a slide on said guide, a lever pivoted at one end on said slide, means to fulcrum said lever on a door, a latch for said lever, a spring acting 25 on said latch and tending to maintain it in latching engagement with the lever, and a spring exerting its pressure on said lever and adapted to be secured to a door, said spring acting on said lever and tending to 30 impart a door-closing movement thereto.

BERNHARD SPITZFADEN.
